UNITED STATES PATENT OFFICE.

KARL CHRISTIAN LASSEN, OF SCHMARGENDORF, NEAR BERLIN, GERMANY, ASSIGNOR
TO THE FIRM OF BERLINER ELEKTROMOBIL-FABRIK G. M. B. H., OF CHARLOTTEN-
BURG, GERMANY.

DRIVING MEANS FOR MOTOR-VEHICLES.

949,828.

Specification of Letters Patent. Patented Feb. 22, 1910.

Application filed February 28, 1908. Serial No. 418,343.

To all whom it may concern:

Be it known that I, KARL CHRISTIAN LASSEN, engineer, citizen of Denmark, residing at 3 Helgolandstrasse, Schmargendorf, near Berlin, Germany, have invented new and useful Improvements in Driving Means for Motor-Vehicles, of which the following is a specification.

The present invention deals with the application of driving-gear to the steering-wheel of a motor-car in which the electro-motor which supplies the driving-power is arranged on the movable supports of the steering-wheel.

In three-wheeled motors of this type the proper placing of the motor is a matter of great difficulty. The motor is usually fixed to the front fork of the frame which however means the use of complicated accessory parts which are anything but ornamental, which take up much space, disturb the balance of the car and make the steering heavy.

The object of the present invention is designed to remove all these disadvantages, and consists of the arrangement of the electro-motor in the same line as the axis of the steering movement.

The drawing shows one of the possible forms of construction.

Figure 1 is a section through motor, frame and steering-wheel, Fig. 2 a side elevation of the same parts.

(1) is the casing of the motor, the axis of which is in a line with that of the steering-movement and passes through the center of the steering-wheel. The front part of the frame is forked, the prongs passing around the motor and supporting it. The two clamping members (9) and (10) hold it in place and are bolted onto the prongs.

At the upper end of the steering-frame (2)

is the casing of the motor, and to this the hand-bar for steering is rigidly fastened. The motor-shaft is hung on ball bearings above and below in the casing (1) of the motor. At the lower end of the motor shaft is a cog-wheel (12) which engages in another cog-wheel keyed onto the counter shaft (13) parallel to the motor shaft. This shaft (13) carries a bevel-wheel (14) at its lower end which engages in a corresponding bevel-wheel (7) which is fastened to the hollow hub (8) of the steering-wheel (15). The shaft (13) is fitted with a universal joint and consists of parts which can be pushed into one another. The system of bevel-wheels is covered by the casing (6) which is at the same time the bearing for the axle (5) of the front wheel. Both bearings of the axle are rigidly connected with the springs (4) and (3) on which rests the frame (2). These springs also support the U shaped piece 2, which serves at the same time as mud-guard.

What I claim and desire to secure by Letters Patent is:

A motor vehicle comprising a frame, a steering wheel, a steering frame pivoted in the first mentioned frame and in which the said wheel is journaled, a motor secured to said steering frame, and having its motor shaft coinciding with the axis of the steering frame, and a steering lever secured upon the upper end of the motor.

In testimony whereof I have signed my name to this specification in the presence of two subscribing witnesses.

KARL CHRISTIAN LASSEN.
